UNITED STATES PATENT OFFICE.

ROBERT M. DUNGAN, OF SANTA ANA, CALIFORNIA.

AIRSHIP.

1,012,529.

Specification of Letters Patent. Patented Dec. 19, 1911.

Application filed November 23, 1909. Serial No. 529,539.

To all whom it may concern:

Be it known that I, ROBERT M. DUNGAN, of the town of Santa Ana, county of Orange, State of California, have invented certain new and useful Improvements in Airships, of which the following is a specification.

My invention pertains to airships, and it has special reference to the aeronef type in which I combine both the aeroplane and helicopter forms for raising and for translating purposes.

In my invention I employ the single plane, in which I use a plurality of propellers or lifting wheels so arranged that they may be inclined at any suitable angles in order to utilize them for lifting purposes or for horizontally translating the ship. These propellers, together with the propelling rudders, coöperate in such a manner, during the initiatory period of flight, that the aeroplane may be raised vertically with its surface horizontally, or it may be inclined so as to utilize the pressure on the aeroplane surface. The lifting wheels are designed to operate through an arc of fully 160 degrees, in the direction of the plane of flight, while the propelling rudder operates through an arc of 90 degrees, thus enabling me to control the flight of the aeroplane under all conditions. In practice I prefer to have four propellers or lifting wheels located substantially equidistant from each other, with the propelling rudder at the rear end, and these several propellers are connected up with the power shaft in such a manner that they may be operated in unison, or independently of each other, and as their planes of rotation are also independently adjustable, I am able to control the lateral as well as the fore and aft stability of the aeroplane when in vertical or in horizontal motion.

As it is well known that an aeroplane when in horizontal translation changes the center of pressure fore and aft, I have devised a simple and effective means to counteract this. The four propellers, which also serve as lifting wheels, are mounted within circular openings formed through the aeroplane. The rear edges of the two forward openings are turned upwardly and project

forwardly, the angle of the hooded structure thus formed being approximately 18 degrees above the horizontal, so that when in flight a certain quantity of air is forced down through the openings, this pressure and volume being varied by the speed of the ship, and as the impinging surfaces thus formed are forward of the middle section of the aeroplane and are constant in their action, whatever the speed may be, the tendency is to neutralize the changing center of pressure, all of which will now be set forth in detail.

In the drawing, Figure 1 is a top or plan view of my improved airship. Fig. 2 is a side view of the same. Fig. 3 is a vertical cross section on line 3 of Fig. 2. Fig. 4 is an enlarged detail view, partly in section, of the propelling rudder and connections. Fig. 5 is a side view, enlarged, of one of the combined propellers and lifting wheels, showing by dotted lines the scope of its movement. Fig. 6 is a top or plan view of the lifting wheel, showing method of swinging the shaft of the propeller. Fig. 7 is a horizontal section of the tubular bow for swinging the propeller, and the connecting end of the shaft. Fig. 8 is a cross section of the tubular bow. Fig. 9 is a longitudinal section of the head and thrust block for the propeller shaft; and Fig. 10 is a top view of the thrust block.

In constructing my invention I provide an aeroplane surface 11, which is preferably made oval-shaped, and its length is, approximately, twice its width. This is so formed that the body centrally is slightly dome-shaped, or made in the form of a shallow inverted dish. The rear end has a circular cutaway portion 12, to receive the propelling rudder 13. This rudder is mounted on a horizontally-disposed shaft 14, (Fig. 4), which shaft passes through a hollow pulley 15, this pulley being connected to the shaft in such a manner that while it turns the shaft, the latter may be swung at any desired angle. For this purpose I slot the shaft, as shown at 16, and place a pair of pins 17 through these slots at right angles to each other, the ends of the pins being secured in the pulley. The hub 18 of the

pulley rests in a journal bearing 19, which is secured by the base 20 to the aeroplane body 11, and the end of the shaft 14 has an operating handle 21. The arms of the 5 handles are adapted to turn on the shaft as shown at 23, thus providing means to throw the propelling rudder to any desired angle without interfering with the rotation of the shaft. Power is imparted to the shaft 10 by a suitable belt on the pulley.

The aeroplane may be made in any suitable manner, preferably of steel tubing, with fabric covering, or in any other manner best adapted for the purpose. Centrally is 15 a housing formed of the base portion 24 which extends below the aeroplane body, and the roof portion 25 which extends above the aeroplane. This housing is about two-thirds the length of the aeroplane, and is 20 about one-third the width of the aeroplane at its widest part. The ends of this housing merge into the aeroplane. Within this housing I locate the machinery and the fuel, and it also serves as a shelter for the occupants 25 of the ship, and for other purposes, and it is my design to provide the housing with suitable doors, windows, and other openings, (not shown), as may be desirable and convenient for operating the ship.

30 As shown in the present instance, I provide four circular openings 27, 28, through the aeroplane, in which the propellers or lifting wheels are mounted. The two forward openings 27 each has its rear edge 35 turned upwardly at an angle forming a hood 29, this hood being thus above the aeroplane surface and adapted to gather a quantity of air, while the aeroplane is in flight, from the upper surface of the aeroplane, and 40 transfer it below the aeroplane and cause it to impinge against the rear propeller.

Each of the propellers 30 is mounted on a shaft 31. In this case I show a four-bladed propeller, but it is obvious that any form 45 may be used. The rear end of the shaft 31 has a head 32 which turns and is held within a thrust block 33. This thrust block is preferably made of two parts bolted together at 34, and the rear end of the block 50 is hinged on a transverse rod or bar 35 which extends across the opening 27, or 28. Adjoining the thrust block the shaft has a pulley 36. The outer or forward end of the shaft is journaled in a sliding block 37, 55 which block is placed loosely on a tubular bow 38. This bow forms an arc fore and aft over the opening; and being concentric with the transverse rod 35 the block 37, in sliding along said bar, will carry with it the 60 end of the propeller shaft, and thus change the plane of rotation of the propeller. To provide a means for so swinging the shaft the bow 38 has a slot 39 on its upper side,

and the sliding block 37 has a tongue 40 which projects down into the slot 39. To 65 this tongue I attach a pair of cords, or, preferably, flexible wires 41 42 which extend in opposite directions down to the base of the bow, where they emerge and pass around grooved pulleys 43 44, secured to the aeroplane, these operating wires extending thence to the housing, (not shown), so they 70 may be within reach of the aviator.

It will be noted that within the superstructure in the central part of the aeroplane, is a cross shaft 46, on which are mounted two pulleys 47. To this shaft I connect the engine 48. In line, fore and aft, with these pulleys 47, are pulleys 49 50, the former of which serves to direct the 80 belts 51 to the pulleys 36, while the latter 50 direct the belts 52 to the pulleys 36 on the rear propellers.

Projecting back from the housing 25 is a 85 pair of arms 53, which extend to a point above the pulley 15, these arms being rigidly held by standards 54. Pulleys 55 are journaled between these arms so as to divert the belt 56 to the pulley 15 on the shaft of the propelling rudder. Thus all the propellers 90 are connected up with a central source of power, the full details of which will be detailed in a subsequent application.

The operation is as follows: I prefer to have the ship mounted on wheels, as shown, 95 for ease in transporting to the launching place, and also in order to keep the aeroplane a sufficient distance above the ground to clear the housing. When ready to ascend the shafts of the propelling or lifting 100 wheels are turned so that they are vertical, thus causing the wheels to rotate on a horizontal plane. The action of lifting wheels under these conditions is such as to raise the entire structure, and when thus 105 freed from the earth the propellers may be inclined forwardly and the propelling rudder also set in motion. If at the same time the forward lifting wheels are accelerated so as to slightly raise the forward end the 110 action of the propelling rudder in directing the ship forwardly, will at once cause a pressure on the lower side of the aeroplane sufficient with the increase in speed, finally, to float the same, when the lifting wheels 115 may be thrown down to act as propeller wheels, in which latter position they are shown in Figs. 1, 2 and 3. As now, in flight, the aeroplane has a low angle, a considerable quantity of air will be transferred 120 from the upper to the lower side of the aeroplane through the action of the hooded structure, and the amount thus transferred varies according to the speed, the greater the speed the greater the pressure across the section of the hood. By this means therefore,

since the center of pressure changes with great rapidity and when the angle of the plane is low, the corrective tendency is more efficient at times when it is of most importance to the fore and aft stability of the moving structure.

It will be observed that the fork of the rear wheel 58 is provided with a vertical rudder 59, as an aid in turning, and the 10 rudder further serves as a means for imparting lateral stability, particularly when sailing into a quartering wind. While the forward lifting wheels are designed to raise or lower either one side or the other and 15 thus correct any lateral instability, it is obvious that the use of the rear rudder will also have a powerful effect while at high speeds, and as the rudder is below the supporting surface the tendency in turning the 20 rudder will be to depress that side of the supporting surface which has the greater angle of incidence, and thus correct the tilting action if it should occur.

What I claim as new, is:

25 1. In an aeronef, a single oval-shaped supporting plane, having four circular openings therein substantially equi-distant from the center, the rear edges of the forward openings projecting upwardly and forwardly to form hoods.

30 2. In an aeronef, a single plane having a plurality of openings and a propeller or lifting wheel in each opening adapted to swing on a vertical fore and aft plane and 35 adjustable to any operative angle within ninety degrees at the will of the operator, the forward openings having the rear edges projecting upwardly at an angle above the body of the plane.

40 3. In an aeronef, a single plane having a pair of openings fore and aft of the transverse middle line of said plane, a semi-circular cutaway portion in its rear end, and a propeller in each opening and in the 45 cutaway portion.

45 4. In an aeronef, a single plane having a pair of openings fore and aft of the transverse middle line, a semicircular cut away portion in its rear end, an adjustable propeller or lifting wheel in each opening, and a propeller in said cutaway portion.

50 5. In an aeronef, a single oval-shaped plane having a pair of openings forward and also a pair of openings to the rear of 55 the middle line, the rear edges of the forward openings having upwardly-projecting, and forwardly-projecting hoods to provide angles of incidence above the plane, to receive air from the upper side of the aero- 60 plane when in horizontal flight.

6. In an aeronef, a single supporting plane, having a dome-shaped curve fore and aft and laterally, and provided with a plu-

rality of openings, each containing a propeller adapted to be adjusted to varying 65 angles, on a vertical plane, and mounted so as to swing above the supporting surface, and upwardly and forwardly-projecting hoods at the rear edges of the forward openings.

7. In an aeronef, a single plane having an upwardly or dome-shaped curve, and provided with a plurality of openings, propellers in said openings, means to swing said propellers on a fore and aft vertical plane, 75 for vertically and horizontally translating said plane, and an adjustable propelling rudder at the rear end of said plane, said plane having an extension which projects rearwardly on each side of the propelling 80 rudder.

8. In an aeronef, a single dome-shaped supporting plane having a pair of openings forward of the center and a pair of openings near the rear end of the plane, the rear 85 edges of the forward openings having forwardly and upwardly-projecting hoods, to provide angles of incidence greater than the body of the aeroplane.

9. In an aeronef, a single plane having 90 an upward or dome shaped curve, provided with a plurality of openings and a propeller or lifting wheel in each opening so mounted as to be adjustable to any angle within ninety degrees on a fore and aft plane, at 95 the will of the operator, and normally swinging above the plane, and a hood projecting upwardly and forwardly at the rear end of the two forward openings to receive the air impact from the propeller when the 100 shaft of the propeller is horizontal.

10. In an aeronef, a single plane having an upward or dome-shaped curve, provided with a pair of openings fore and aft and a semi-circular cutaway portion in its rear 105 end provided with a propeller in each opening and in the cutaway portion.

11. In an aeronef, a single plane having an upward or dome-shaped curve, provided with a pair of openings fore and aft, and a 110 semicircular cutaway portion in its rear end, and a propeller or lifting wheel in each opening, and a propeller in said cutaway portion.

12. In an aeronef, a single supporting 115 plane, oval-shaped having an upward or dome-shaped curve, with four adjustable propellers therein mounted to swing above the plane, and centrally a housing which projects above and below said plane.

13. In an aeronef, a single plane having centrally a longitudinal housing extending above and below said plane, a pair of openings at the forward end of said housing and a pair of openings at the rear end thereof, 125 the rear edges of the forward pair of open-

- ings having upwardly-projecting hoods, said plane having a cutaway portion in its rear end and an adjustable propeller therein.
14. In an aeronef, a single plane having centrally a longitudinal housing extending above and below the plane, a pair of openings at the forward end of the housing and a pair of openings near the rear end of the housing, lifting wheels in said openings adjustable as to angle, on vertical fore and aft planes, and a propeller on the rear end of the plane adjustable to swing vertically and horizontally.
15. In an aeronef, a single plane having centrally a longitudinal housing extending above and below said plane, provided with a plurality of openings near each end of the housing and a propeller or lifting wheel in each opening so mounted as to be adjustable on a fore and aft vertical plane, to any angle within ninety degrees, at the will of the operator, and an upwardly and forwardly projecting extension of the main plane behind each of the forward propellers.
16. In an aeronef, a single plane having centrally a longitudinal housing extending above and below said plane, provided with four openings, two at the forward end and two at the rear end of the housing, and a propeller in each opening, the rear end of said plane having a semicircular cut-away portion and an angularly-adjustable propeller in said cutaway portion.
17. In an airship, a single plane having centrally a longitudinal housing extending above and below said plane, provided with a pair of openings at the forward end of the housing and a pair of openings at the rear end of said housing, a semi-circular cutaway portion in the rear end of the plane, and a propeller in each opening and in the cutaway portion, said propeller in the cutaway portion being adapted to swing horizontally and vertically, and the propellers in the circular openings being adapted to swing on a vertical fore and aft plane.
18. In an aeronef, a single plane having centrally a longitudinal housing extending above and below the plane, provided with a pair of openings at the forward end of the housing and a pair of openings near the rear end thereof, the forward pair of openings having at their rear edges projecting hoods to provide angles of incidence greater than the body of the plane, a semicircular cutaway portion at the rear end of the plane, an adjustable propeller or lifting wheel in each opening, and a propelling rudder in the rear cutaway portion.
19. In an aeronef, a single oval-shaped plane, the body of which is slightly dome-shaped fore and aft and laterally having centrally a longitudinal housing extending above and below the plane, with adjustable propelling and lifting means in said plane mounted to swing above the plane, and power in said housing.
20. In an aeronef, a single plane having an upward or dome-shaped curve, provided centrally with a longitudinal housing extending above and below the plane, four approximately equidistant openings in said plane, and a propeller in each opening, and means for swinging same on a vertical fore and aft plane.
21. In an aeronef, a single oval-shaped plane having an upward or dome-shaped curve, provided centrally with a longitudinal housing extending above and below said plane, a plurality of openings in said plane, and adjustable propeller in each opening, and an adjustable propeller at the rear end of said plane.
22. In an aeronef, a single oval-shaped plane, having an upward or dome-shaped curve, provided centrally with a fore and aft housing which extends above and below said plane, and a plurality of openings in said plane, a propeller in each opening and means for swinging said propeller on a fore and aft vertical plane.
23. In an aeronef, a single oval-shaped plane having an upward or dome-shaped curve, provided centrally with a longitudinal housing, a pair of openings at the forward end of the housing and a pair of openings near the rear end thereof, the rear edges of the forward pair of openings having hoods which project above the oval-shaped plane, and a propeller at the rear end of the plane adapted to change the angle or the direction of flight.
24. In an aeronef, a single plane having an upward or dome-shaped curve and provided centrally with a longitudinal housing extending above and below the plane, said plane being provided with a plurality of openings, a propeller in each opening, and an adjustable propeller on the rear end of said plane.
25. In an aeronef, a single plane having an upward or dome-shaped curve, and centrally a longitudinal housing extending above and below the plane, a pair of openings fore and aft through the plane on each side of the housing, and a semicircular cutaway portion in its rear end provided with a propeller, and a propeller in each opening.
26. In an aeronef, a single plane having an upward or dome-shaped curve, and a central longitudinal housing extending above and below the plane, a pair of openings fore and aft through the plane, a semicircular cutaway portion in its rear end an adjustable propeller or lifting wheel in

each opening, and a propeller in said cut-away portion.

27. In an aeronef, a single oval-shaped plane, having an upward or dome-shaped curve, provided centrally with a longitudinal housing extending above and below the plane, a pair of openings at the forward end of the housing and a pair of openings near the rear end thereof, the rear edges of the forward openings having hoods which project up beyond the oval-shaped plane to re-

ceive air from the upper side of the aeroplane while in flight, and an adjustable propeller at the rear end of the plane to change the angle or the direction of flight.

Signed this 16 day of October, 1909, in the presence of witnesses.

ROBERT M. DUNGAN.
